UNITED STATES PATENT OFFICE

159,430

COMB

Peter J. Morroni, Leominster, Mass.

Application January 5, 1949, Serial No. 61

Term of patent 3½ years

(Cl. D86—8)

To all whom it may concern:

Be it known that I, Peter J. Morroni, a citizen of the United States, residing at Leominster, in the county of Worcester and State of Massachusetts, have invented a new, original, and ornamental Design for Comb, of which the following is a specification, reference being had to the accompanying drawing, forming part thereof.

Fig. 1 is an edge view of a comb;

Fig. 2 is a view in front elevation; and

Figs. 3 and 4 are sectional views, taken respectively, on lines 3—3 and 4—4 of Fig. 2, of a comb, showing my new design.

It is understood that the comb teeth shown in full lines are to extend over the area delineated by the broken lines in Fig. 2.

I claim:

The ornamental design for a comb, as shown and described.

PETER J. MORRONI.
